UNITED STATES PATENT OFFICE.

WILLIAM BAINES, OF LONDON, ENGLAND.

HYDROCARBON-VAPORIZER FOR EXPLOSIVE-ENGINES.

SPECIFICATION forming part of Letters Patent No. 644,027, dated February 20, 1900.

Application filed September 18, 1899. Serial No. 730,890. (No model.)

To all whom it may concern:

Be it known that I, WILLIAM BAINES, a subject of the Queen of England, residing at London, England, have invented certain new and 5 useful Improvements in Vaporizers for Internal-Combustion Engines, (for which I have made application in Great Britain under No. 18,961, dated September 5, 1898,) of which the following is a specification.

10 My invention has relation to a vaporizer for internal-combustion engines, adapted also to serve as a silencer for the exhaust-gases from the engine; and among the objects in view is to provide a device of the described 15 character whereby the exhaust-gases from the engine are caused to pass therethrough and at the same time heat the hydrocarbon to be vaporized whether the latter is mixed with the air or not. Thus the heat of the exhaust 20 is utilized for vaporizing the hydrocarbon and mixing it with the air in a manner peculiarly suitable for the heavier mineral oils, while the temperature of the exhaust is reduced, causing less noise and smell.

25 The invention consists in the novel construction, arrangement, and combination of parts, as hereinafter described, illustrated in the drawings, and pointed out in the appended claims.

30 In the drawings, Figure 1 is a sectional view, partly in elevation, of a device embodying my invention. Fig. 2 is an elevation, partly in section, on line 4 4 of Fig. 1.

35 My vaporizer, which also performs the function of an exhaust-silencer, comprises a casing D, having a casing F⁸ secured thereto at one end, the two forming practically one casing and the construction being such that the exhaust-gases entering the silencer at the inlet D' impinge on the dividing-wall F', which is arranged as shown, whereby to form the 40 chamber F. The chamber F is divided by a horizontal septum F⁴ into two compartments F² F³ communicating at F⁵. The oil and the 45 air are admitted into the upper chamber F² through the inlet-tube F⁶, pass into the lower chamber F³, and being heated and vaporized in these chambers by the exhaust-gases pass

as an explosive mixture into the explosion-chamber of the motor through the outlet F', 50 which is in practice to be connected in any suitable manner to the inlet-valve of the motor.

Desirably the exhaust-gases pass from the casing D into the atmosphere through an as- 55 bestos cloth, as shown at D².

It is evident that the chamber F may, if desired, be divided into more than two compartments by additional septa, such as F⁴, so as to give greater length of travel to the 60 mixture of oil and air.

What I claim as my invention, and desire to secure by Letters Patent, is—

1. In a device of the character described, the combination with the casing of an ex- 65 haust-silencer, having an inlet at one end for admission of exhaust-gases and an outlet at the opposite end for the said gases, of a partition F' within the casing, a second partition F⁴ forming the chambers F² F³ communicat- 70 ing with each other at one end, the chamber F² communicating with an inlet for the explosive charge, and the chamber F³ communicating with an outlet for the said charge.

2. In a device of the character described, 75 the combination with the casing of an ex-haust-silencer comprising the casing D hav- ing an outlet at one end for exhaust-gases, and a casing F⁸ secured to the casing D at one end and provided at the opposite end 80 with an inlet for admission of the exhaust-gases, of a partition F' within the casing F⁸ and a partition F⁴ forming two chambers F² F³ communicating at one end with each other 85 through opening F⁵, said chamber F² com-municating at the opposite end with the inlet for the oil and air and the corresponding end of chamber F³ communicating with the outlet for the vaporized oil and air.

In testimony whereof I have signed my 90 name to this specification in the presence of two subscribing witnesses.

WILLIAM BAINES.
